UNITED STATES PATENT OFFICE.

JAMES O'CONNOR, OF NEW YORK, N. Y.

TRACKER-BOARD AND NOTE-SHEET MECHANISM FOR MECHANICAL MUSICAL INSTRUMENTS.

No. 926,679.

Specification of Letters Patent.

Patented June 29, 1909.

Application filed April 20, 1903. Serial No. 153,404.

To all whom it may concern:

Be it known that I, JAMES O'CONNOR, a citizen of the United States, and resident of New York, in the county of New York and State of New York, have invented certain new and useful Improvements in Tracker-Boards and Note-Sheet Mechanism for Mechanical Musical Instruments, of which the following is a full, clear, and exact specification.

This invention relates to the tracker board mechanism of mechanically operated musical instruments and other instruments employing controlling sheets which are perforated 15 in accordance with certain standards or scales.

The object of the invention is to provide means for using, with the same note sheet mechanism, sheets or rolls of different standards of width and spacing of their actuating perforations, or other controlling devices, and to provide means whereby the change to adapt the mechanism from a sheet of one standard to that of another may be quickly 25 and easily made.

The invention is herein shown and described as applied to the note sheet mechanism of an automatically operated piano player.

Figure 1 of the drawings is a plan of a portion of an ordinary note sheet mechanism, the sheet being partly cut away and showing two tracker boards of different width and scale, one of which is shown in operative 30 relation to the sheet. Fig. 2 is a plan of the same mechanism showing the other tracker board in operative position, and showing a note sheet of corresponding scale in connection therewith. Figs. 3 and 4 are, a side view and an end view respectively, in enlarged scale, of part of the sheet mechanism, showing one method of providing for the use of two or more independently removable tracker boards. Figs. 5 and 6 are similar 45 views of a modified way of mounting the tracker boards. Figs. 7 and 8 are views of a method for providing for the use of three or more tracker boards in the same mechanism. Figs. 9 and 10 are views of another 50 modified form of the apparatus, Fig. 9 being an end view in section on the line 9, 9 of Fig. 10, and Fig. 10 being a side view.

Figs. 11 and 12 are views of further modifications, Fig. 11 being an end view through the line 11, 11 of Fig. 12, and Fig. 12 a side 5 view.

The side views 4, 6, 8, 10 and 12 each show the construction of only one end of the various mechanisms, a similar construction at the other end being understood. 60

The two tracker boards 27 and 28 rest on seats 32 and 33 in the two swinging blocks 29 which are pivotally supported by the studs 30 appurtenant to the uprights 24. Connection with the usual pneumatic note 65 sounding devices shown in section in Fig. 3 is made in this case by means of the rubber tubes 31 which are forked at their upper ends, the fork ends 34 and 35 fitting the stems 36 and 37 leading from the corresponding apertures 38 and 39 in the two 70 tracker boards.

In Figs. 1, 3 and 4, the tracker board 27 is shown in operative relation to the sheet 24, the hinged cover 40 being thrown back 75 to expose the apertures, while the board 28 is below and away from the note sheet, its apertures being closed by the cover 41 which thus prevents the passage of any air through these apertures to the note sounding mechanism. When it is desired to adapt the mechanism to the music sheet 20 fitting the tracker board 28, the cover 40 is closed down, the supporting blocks are swung to the position shown in Fig. 2, and the cover 41 is 85 thrown back leaving the tracker board 28 in position for the new sheet. Should it be desired to make use of additional tracker boards, one or both of the boards 27 and 28 may be removed from the seats 32 or 33 and 90 replaced by the desired boards. The holding screws 42 and 43 have their heads flattened off on one side as shown, so that a half turn suffices to release the boards from or 95 secure them to their respective seats.

In order to provide means for the ready adjustment of the driving and rewinding mechanism to the varying widths of the rolls carrying the note sheets of different standards of spacing, the ends of the roll shafts 89 100 are supported in adjustable sockets 90 and 91. In the case of the sockets 90, the roll shafts 89 are keyed or otherwise secured to it for driving and rewinding, the sockets 90

being held in the bushings 92 journaled in the uprights 21, and secured to the driving and rewinding gears 25 and 26 respectively. The length of the sockets 91 is sufficient to 5 allow adjustment in the bushings 92 toward and away from the longitudinal center line of the note sheet 24, thus adapting them to any desired width of roll. The bushings 92 are provided with set screws 94 or other suitable means for securing the sockets in position. The sockets 91 and the bushings 93 are 10 of similar construction except that no provision for driving or rewinding need be made at these ends of the rolls, the sockets, and bushings being preferably stationary and 15 not rotating with the shafts.

The construction shown in Figs. 5 and 6 operates substantially the same as that of Figs. 1, 2, 3 and 4. The two tracker boards 20 in this case are joined in an integral structure 44, each pair of apertures 45 being connected by a channel 19 leading to a stem 46 to which the operating tube 47 is attached. The bands or strips 48 of rubber or other 25 suitable material are supported on rods 18 in the uprights 21 and so disposed as to cover the face of whichever board is out of use. The tracker board 44 may be replaced by one of similar construction by removing it 30 from the swinging support 49. Figs. 7 and 8 show a construction substantially identical with that of Figs. 5 and 6 except that in this instance three tracker boards are joined in an integral structure 50 and a modified form 35 of aperture cover 51 is used.

In the construction shown in Figs. 9 and 10, the tracker boards 56 and 57 are arranged to slide in and out of operative position in the slots 58 and 59 provided in the 40 supports 60, appurtenant to the uprights 21. The bottom of each tracker board rests on the rockers 61 secured to the rock shaft 62 which is supported in the uprights 21. The rockers 61 are provided with lugs 63 and 64 45 which act as stops to limit the movement of the rockers by coming in contact with the overhanging portions 72 on the support 60. Connection with the note sounding devices is made in a similar manner to that shown in 50 Figs. 3 and 4, by means of forked rubber tubes 55 which fit the stems 65 and 66 leading from the corresponding apertures 67 and 68 in the two tracker boards. The tracker board 56 is here shown in operative relation 55 to the sheet 24 while the board 57 is in a lower position away from the sheet with its apertures closed by the swinging cover 70, pivoted on the rod 73 and held in place by the spring 71 whose other end is secured to 60 the cover 69. When the cover 70 is in the position shown, it prevents any upward movement of the board 57 and therefore serves to lock all the parts in the operative position shown, since the board 56 cannot 65 move downward without communicating by

means of the rocker 61 an upward movement to the board 57, and any movement in the opposite direction is prevented by the position of the lug 63 against the projection 72.

When it is desired to bring the tracker board 57 into operative position, the cover 70 is pushed back, allowing the board to rise as the board 57 is pushed down, the cover 69 being drawn over the top of the latter by the spring 71, as soon as it reaches its lowest position. Either tracker board may be removed entirely by releasing the tubes from their stems and lifting the board out of the slots 58 and 59. In Fig. 11 the tracker board 78 is stationary, being secured to the 75 uprights 21, while the tracker board 77 is movable, being supported by the parallel links 80 secured to the ends of the boards 77 and 78, the latter having recesses 81 to permit the necessary movement of the links. 80 Springs 82 supported by the uprights 21 hold the tracker board 77 either in or out of operative position, the movement of the board 77 being limited in both directions by contact with the board 78. As the free adjustment 85 of the links 80 is liable to permit some end movement of the board 77 and thus interfere with the accurate registering of the note sheet over the apertures, the tongues 87 secured to the board 77 are preferably provided which fit in slots 86 in the board 78, and thus prevent any end movement. Hinged covers 83 are provided to close the 90 operative apertures when not in use. Connection with the operating devices is made 95 by tubes in a similar manner to that described in Figs. 3, 4, 9 and 10. When it is desired to bring the tracker board 78 into operative position, the board 77 is pushed down to its lowest position, thus leaving a free passage 100 for the note sheet over the top surface of the board 78.

I claim as my invention:—

1. The combination with note sheet mechanism, of a tracker board and means for 110 mounting the tracker board to move it laterally into and away from operative relation to the note sheet.

2. In combination with note sheet mechanism, of a plurality of tracker boards, 115 mounted for movement into and out of operative relation to the note sheet.

3. The combination with note sheet mechanism, of a plurality of tracker boards, and means for mounting the tracker boards to 120 move either of them into and out of operative relation to the note sheet.

4. The combination with note sheet mechanism, of a tracker board mounted for swinging movement into and out of operative relation to the note sheet. 125

5. The combination with note sheet mechanism, of a plurality of tracker boards mounted for swinging movement into and out of operative relation to the note sheet. 130

6. The combination with note sheet mechanism, of a plurality of tracker boards, and means for mounting the said boards to move one of them into and another out of operative relation to the note sheet.
7. The combination with note sheet mechanism, of a plurality of tracker boards and a holder for receiving the boards mounted to carry one of said boards into and another of said boards out of operative relation to the note sheet.
8. The combination with note sheet mechanism, of a tracker board movable laterally into and away from contact with the note sheet, and means for covering the apertures of the tracker board when in its inoperative position.
9. The combination with note sheet mechanism, of a plurality of tracker boards, means for mounting the said boards to move either of them into and another out of operative relation to the note sheet, and means for covering the tracker board apertures when out of operative relation to the sheet.
10. The combination with note sheet mechanism, of a plurality of tracker boards, a holder for supporting the plurality of boards, means for simultaneously moving either of said tracker boards into, and another board out of operative relation to the note sheet.
11. The combination with note sheet mechanism, of a plurality of tracker boards, a holder therefor mounted for swinging movement to carry either of the said boards into, and the remaining board or boards out of operative relation to the note sheet, and means for covering the apertures of the unused boards when out of operative position.
12. In an instrument of the character referred to, a plurality of movable trackers, and means connected thereto for projecting one thereof into, and retracting another thereof out of, operative position.
13. The combination, in a music playing instrument, of a plurality of trackers, including a movable tracker, and means for projecting the movable tracker into and out of operative position.
14. The combination, with a music playing instrument, of a plurality of trackers, including a movable tracker, and means for transferring the control of the said instrument to any of said trackers.
15. The combination, with a music playing instrument, of a plurality of music sheets arranged in different scales, a plurality of trackers therefor, including a removable tracker, and means for interposing the appropriate tracker between either music sheet and the instrument.
16. The combination, in a music playing instrument, of a plurality of trackers, including a removable tracker, a set of pneumatic devices, and means for transferring the control of the said pneumatic devices to any of said trackers.
17. The combination with music sheet mechanism, of a plurality of tracker boards and a holder for interchangeably receiving and supporting the plurality of tracker boards.
18. The combination of a plurality of trackers, including a movable tracker, and means for stopping air communication through the air apertures of either tracker.
19. The combination of a plurality of trackers, including a movable tracker, a series of air apertures for each tracker, pneumatic devices for the trackers, and means for stopping communication from the air apertures of either tracker to the said pneumatics.
20. The combination of a plurality of trackers, including a movable tracker, each provided with air apertures, pneumatic devices for the said trackers, and means for establishing the air communication through the air apertures of either tracker.
21. The combination of a plurality of trackers, including a movable tracker, air apertures for the respective trackers, pneumatic devices, and means for establishing air communication between the said pneumatic devices and the air apertures of either tracker, and for stopping air communication from the apertures of the other trackers.
22. The combination of a plurality of trackers, including a movable tracker, each provided with a row of air apertures, a set of pneumatic valve actuating devices, and means for controlling said pneumatic devices from either row of tracker apertures independently of the other row.
23. The combination of tracker devices provided with two rows of apertures, including a movable tracker, the apertures in the respective rows being formed on different scales, a set of pneumatic valve actuating devices, and means for controlling said pneumatic devices from either row of said tracker apertures, independently of the other row.
24. A tracker device, having a plurality of rows of air apertures, one of which is movable, the apertures being formed on different scales for the respective rows, pneumatic devices for connecting with the said apertures, and means for separately shutting off the said rows of apertures from the said pneumatic devices.
25. The combination, with a series of pneumatic actions, of tracker devices, including a movable tracker having a plurality of rows of apertures ranged on different scales in the respective rows, pneumatic devices for the said apertures, and means for separately shutting off communication through the respective rows of apertures to the said pneumatics.
26. A tracker device mounted for swinging movement, and having a plurality of rows of

- tracker apertures, pneumatic devices for communicating with the said apertures, and means for separately shutting off the communication through either row of apertures.
27. A tracker device mounted for swinging movement and having a plurality of rows of apertures ranged on different scales, in combination with flexible pipes connecting with the respective rows of apertures, to permit of the said swinging movement.
28. A tracker device mounted for swinging movement, and having a plurality of rows of apertures ranged on different scales, pneumatic devices, and flexible pipes connecting the said pneumatic devices with the respective rows of apertures.
29. A tracker device mounted for swinging movement, and having a plurality of rows of air apertures ranged on different scales, pneumatic actions, and flexible pipes for the respective pneumatic actions, provided with branches leading to corresponding apertures in the two rows of apertures.
30. A tracker device mounted for swinging movement and provided with a plurality of rows of tracker apertures, and means for registering the swinging tracker with its rows
- of apertures in their respective operating position.
31. A tracker mounted for swinging movement and provided with a plurality of rows of tracker apertures, means for registering the tracker at different portions of the swinging movement to bring the respective rows of apertures into operative position, and means for stopping air communication through the rows of apertures when out of operative position.
32. A tracker device mounted for swinging movement and provided with a plurality of rows of tracker apertures, means for registering the tracker device at positions in its swinging movement with the rows of apertures at their respective operative positions, and means disposed at the inoperative positions of the rows of apertures for stopping air communication through them when in those positions.
